UNITED STATES PATENT OFFICE

JOHN DRENTHE, OF CHICAGO, ILLINOIS

DESIGN FOR A MAT OR SIMILAR ARTICLE

Application filed April 24, 1931. Serial No. 39,612. Term of patent 14 years.

To all whom it may concern:

Be it known that I, JOHN DRENTHE, a citizen of the United States, residing at Chicago, in the county of Cook and State of Illinois, have invented a new, original, and ornamental Design for a Mat or Similar Article, of which the following is a specification, reference being had to the accompanying drawing, forming a part thereof, and in which the figure is a plan view of a mat or similar article showing my new design.

I claim:

The ornamental design for a mat or similar article, as shown.

JOHN DRENTHE.
